CLAIM

The ornamental design for a teppanyaki grill, as shown and described.

DESCRIPTION

FIG. 1 is a front perspective view of a teppanyaki grill, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of portion 9 in FIG. 1; FIG. 10 is an enlarged detail view of portion 10 in FIG. 1; and,

FIG. 11 is an enlarged detail view of portion 11 in FIG. 1. The broken lines show portions of the teppanyaki grill that form no part of the claimed design.
